UNITED STATES PATENT OFFICE.

FREDERICK W. HODGES, OF DETROIT, MICHIGAN, ASSIGNOR TO DETROIT LUBRICATOR COMPANY, OF DETROIT, MICHIGAN, A CORPORATION OF MICHIGAN.

CARBURETER.

1,159,029.

Specification of Letters Patent.

Patented Nov. 2, 1915.

Application filed May 3, 1915. Serial No. 25,483.

To all whom it may concern:

Be it known that I, FREDERICK W. HODGES, a citizen of the United States of America, residing at Detroit, in the county of Wayne 5 and State of Michigan, have invented certain new and useful Improvements in Carbureters, of which the following is a specification, reference being had therein to the accompanying drawings.

10 The invention relates to carbureters of that type in which the flow of the liquid fuel into the mixing chamber is regulated by a metering pin and a coöperating air valve.

It is the object of the invention to obtain 15 a construction in which there is an instantaneous response to the opening of the throttle by a corresponding increase in the flow of liquid, and also one in which there is a similar response to the closing of the throttle by an instantaneous checking of the flow of the liquid. Thus the construction is one 20 which avoids the starving of the mixture when the throttle is quickly opened, and the choking by over-enrichment when the throttle is quickly closed.

In the drawings: Figure 1 is a longitudinal section through the carbureter when the throttle is in closed or idling position; Fig. 2 is a similar view showing the relation of 30 the parts when the throttle has been suddenly opened; and Fig. 3 is a similar view showing the relation of parts when the throttle is stationary in an open position.

A is the casing of the carbureter which 35 contains the mixing chamber B, having the air-inlet C controlled by the automatic air-valve D, and a throttle E above the mixing chamber controlling communication between the same and the engine induction conduit. 40 The valve D has a conical head, which initially rests upon an annular seat F at the lower end of the mixing chamber. The valve is also provided with a stem G slidably engaging a tubular guide H in the casing, and having a central passage I for the oil or liquid fuel that enters the mixing chamber.

J is a tapering metering pin extending 50 into the passage I and coöperating with the stem G to vary the restriction of the oil passage in different positions of adjustment of the valve D.

With the construction as thus far described, whenever there is an air suction 55 communicated to the mixing chamber B the

valve D will be lifted from its seat, permitting the flow of air into said chamber, and simultaneously the liquid fuel will enter through the passage I, its flow being controlled by the metering pin J. This will 60 normally proportion the flow of the liquid to that of the air where there is a gradual opening or closing of the throttle, but upon the sudden opening of the throttle the greater inertia and frictional resistance of 65 the liquid will prevent it from keeping pace with the sudden increase in flow of air, so that a lean mixture results. To avoid this result I have provided a dash-pot for resisting the sudden upward movement of the 70 valve D, and have utilized the resistance of the dash for adjusting the metering pin to permit increased flow of the liquid. The construction is also such that the suction of the dash is almost instantaneously relieved 75 upon cessation of movement of the valve D, which avoids flooding or an over-rich mixture.

The specific construction preferably employed for accomplishing the result as above 80 described is the arrangement of a cylinder or dash-pot K below the air-inlet C and in communication through a passage L with the float-controlled oil chamber M. Within this cylinder or dash-pot is a piston N which is 85 connected to the stem G, and is therefore adjusted with each movement of the valve D.

O is a cylindrical recess formed in the lower portion of the stem G for receiving a 90 piston P which is mounted upon the metering pin.

Q is a shank for the metering pin passing through an adjustable bearing R and having a spring S sleeved thereon between the piston and said bearing. A pin Q' carried by the lower end of the shank Q is adapted to bear against the lower end of R to limit upward displacement of the piston P and metering pin, without restricting downward motion of said parts.

T is a pinion engaging the rack face in the bearing R to adjust the position of the same and effect a corresponding adjustment in position of the metering pin.

With the construction just described the cylinder or dash-pot K has a vent connection with the cylindrical recess O above the piston P, formed by ports O', and the piston N is provided with such clearance within the cylinder K as to permit a slow leakage of 105 110

the liquid thereabout. This will result in the formation of a liquid dash-pot for resisting a sudden rise of the valve D, while a gradual rise is still permitted by the leakage of the liquid about the piston N. Whenever there is a sudden rise of the valve D, due to the sudden opening of the throttle, the suction of the dash-pot which is communicated to the piston P will draw the latter downward in the cylinder O against the resistance of the spring S, and by lowering the metering pin J will increase the flow of the oil. This will continue as long as the throttle E is being opened, but the instant 10 that the throttle assumes a stationary position further upward movement of the valve D is prevented, and the leakage of liquid about the piston N will equalize the pressure above and below the piston P, permitting 15 the spring S to again restore said piston and the metering pin J to normal position. This normal position of the metering pin is unaffected by the position assumed by the valve D, nor is it affected to as great an extent by 20 the gradual movement of said valve. It is only when there is a sudden movement upward that the dash-pot becomes effective to draw the piston P downward and to displace the metering pin. 25 30 In idling position or where the valve D is seated, the air passes through channels U in the valve head, and is discharged adjacent to the nozzle end V of the passage I; but this construction forms no part of the present 35 invention.

What I claim as my invention is:—

1. In a carbureter, the combination with a casing containing the mixing chamber, of a valve controlling the air inlet to said chamber, a nozzle for discharging the liquid fuel into said chamber, means for varying the flow of the liquid fuel with each change in position of the air valve, and means for additionally increasing the flow of the oil upon 40 a sudden opening of said air valve and for restoring the normal flow upon the cessation of said sudden movement.
2. In a carbureter, the combination with a casing containing the mixing chamber, of 45 an automatic valve, controlling the air inlet to said chamber, a nozzle for discharging liquid fuel into said chamber, a metering pin and coöperating means carried by said automatic valve for variably restricting the flow of liquid fuel to said nozzle in different 50 positions of adjustment of said valve, a dash-pot for resisting the sudden opening of said automatic valve, means actuated by the suction of said dash-pot for adjusting said 55 metering pin to further increase the flow of liquid fuel, and means for quickly returning said metering pin to its normal position upon cessation of the suction of said dash-pot.
3. In a carbureter, the combination with a 60 casing containing the mixing chamber, of 65

an automatic valve controlling the air inlet to said chamber, a nozzle for discharging liquid fuel into said chamber, a metering pin and coöperating means carried by said automatic valve for variably restricting the flow of liquid fuel to said nozzle, a suction dash pot for resisting the sudden opening of said valve adapted to quickly lose its suction upon cessation of movement of said valve, means actuated by the suction of the dash 70 pot for adjusting said metering pin to further increase the flow of the liquid, and means for quickly restoring said metering pin when said suction ceases. 75

4. In a carbureter, the combination with a casing containing the mixing chamber, of an automatic valve for controlling the air inlet to said chamber, a nozzle for discharging liquid fuel into said chamber carried by said valve, a stem for said valve 80 having a passage therethrough for the liquid to said nozzle, a piston on said stem, a stationary cylinder for said piston, coöperating therewith to constitute a dash-pot, a cylindrical recess in said stem and piston, 85 a piston in said recess, a metering pin mounted on said latter piston and variably restricting the passage through said stem in different positions of adjustment of said valve, and means for yieldably holding said 90 metering pin and its piston stationary, permitting movement thereof under the suction of said dash-pot to temporarily increase 95 the flow of liquid.

5. In a carbureter, the combination with a casing containing the mixing chamber, of an automatic valve controlling the air inlet to said chamber, having a stem with a passage therethrough for the liquid fuel, a piston on said stem, a stationary cylinder 100 for said piston coöperating therewith to form a dash-pot, a similar piston engaging a cylindrical recess in said large piston and stem, a metering pin carried by said small piston for variably restricting the liquid passage through said stem, a stem depending from said small piston, a spring sleeved thereon, and an adjustable member forming a guide for said stem and an abutment for 105 said spring, for the purpose described. 110

6. In a carbureter, the combination with a casing containing the mixing chamber, of an automatic valve controlling the air inlet to said chamber, a nozzle for discharging the liquid fuel into said chamber, means for varying the flow of liquid fuel with each change in position of said air valve, a dash-pot for resisting the sudden opening of said valve, and means operated by the suction of said dash-pot during the sudden movement of said valve for temporarily increasing the flow of liquid, said increased flow ceasing on cessation of movement. 115

7. In a carbureter, the combination with a casing having a mixing chamber, a nozzle 120

for discharging liquid fuel into said chamber, a piston and cylinder forming a dash-pot, means operating upon a sudden increase in the velocity of air passing through 5 the mixing chamber, producing a suction stroke of the piston, a second piston within that of the dash-pot, and actuated through the suction of the first piston, and means actuated by said second piston for varying 10 the supply of oil to said nozzle.

8. In a carbureter, the combination with a casing containing a mixing chamber, a valve controlling an air inlet into said chamber, a nozzle for discharging liquid 15 fuel into said chamber, a dash-pot for resisting the sudden opening of said air valve and comprised of a cylinder and piston, a second piston axially movable within the dash-pot piston and actuated by motion of 20 the dash-pot piston, and means operating upon a displacement of the second piston for varying the fuel supply to the nozzle.

9. In a carbureter, the combination with 25 a casing containing a mixing chamber, and an air chamber, of an automatic valve controlling an inlet to the mixing chamber, a cylinder adjacent the air chamber, a stem

extending from said valve through the air chamber and into said cylinder, a piston carried by the stem within said cylinder, said 30 piston and cylinder forming a dash-pot, means for supplying liquid fuel to the mixing chamber, and means acting upon a displacement of said piston in its cylinder to vary the fuel supply to the mixing chamber. 35

10. In a carbureter, the combination with a casing having a mixing chamber, of a valve automatically controlling an air inlet to said chamber, a stem extending from said valve formed with a passage for conducting liquid fuel to the mixing chamber, and formed with a chamber in communication with said passage, a piston mounted in said chamber, means for restricting said passage connected with the piston, and means actuated by a displacement of said valve, producing an opposite displacement of said piston. 40 45

In testimony whereof I affix my signature in presence of two witnesses.
